CLAIM

The ornamental design for a light as shown and described.

DESCRIPTION

FIG. 1 is a top perspective view of a light, showing our new design.

FIG. 2 is a bottom perspective view.

FIG. 3 is a front side view, with the rear, left, and right side views being identical to the front side view.

FIG. 4 is a top view thereof; and,

FIG. 5 is a bottom view thereof.

The evenly-spaced broken lines illustrate portions of the light and the zig-zag broken lines along the downrod illustrate a symbolic break in length. Neither of the broken line disclosures or the space in between the symbolic break form part of the claimed design.

1 Claim, 5 Drawing Sheets
